INVENTOR—

Henry M. Loomer
By his Attorney,
Nelson W. Howard

UNITED STATES PATENT OFFICE.

HENRY M. LOOMER, OF BEVERLY, MASSACHUSETTS, ASSIGNOR TO UNITED SHOE MACHINERY CORPORATION, OF PATERSON, NEW JERSEY, A CORPORATION OF NEW JERSEY.

BURNISHING-MACHINE.

1,395,285.

Specification of Letters Patent.

Patented Nov. 1, 1921.

Application filed January 10, 1920. Serial No. 350,607.

To all whom it may concern:

Be it known that I, HENRY M. LOOMER, a citizen of the United States, residing at Beverly, in the county of Essex and State 5 of Massachusetts, have invented certain Improvements in Burnishing-Machines, of which the following description, in connection with the accompanying drawings, is a specification, like reference characters on 10 the drawings indicating like parts in the several figures.

This invention relates to retaining members and is disclosed as embodied in a member for retaining upon its carrier an edge 15 setting tool for burnishing the sole edges of boots and shoes. It is necessary that such tools be easily detachable from their carriers since they are profiled to suit the shape of the particular style of sole edge being treated, and have to be changed frequently, as different styles of shoes come to 20 the edge setting machine.

The carrier and tool are ordinarily made to telescope together, with a groove in one 25 member, and the retaining member is mounted on the other member and engages the groove to hold the former member in position. It has been proposed to use a flat leaf spring for this purpose having a curved 30 portion at its end to engage the groove. It has been found, however, that these springs soon break in use. One reason, among others, contributing to this lack of durability is that there is always more or less rocking 35 of the edge setting tool around the axis of its telescoping connection to the carrier or spindle, due to the movement of the shoe in the hands of the operator, and the continual twisting of the spring finally resulted in 40 its breaking.

It has been proposed also to form the retaining member of a U-shaped wire having a roller mounted at its middle point for engagement in the groove. This device has 45 proved to be too expensive to manufacture and has not gone into general use. It has also been proposed to form the retaining member of a single piece of piano wire, bent in a helix at its central portion, and having 50 its ends extending, in parallelism, to the at-

taching screw. This has proved perfectly successful as regards wear, temper, effectiveness and cheapness of manufacture.

The twisting and turning of the shoe in the operator's hand during the edge-setting 55 operation gives rise to an oscillation of the tool around the axis of the telescope joint. It is not practically feasible (and is probably undesirable) to eliminate this rocking movement between the tool and its support, and it is a primary object of the present invention to provide a retaining member 60 which will combine the advantages of prior constructions and provide for this relative movement, while at the same time 65 avoiding any wearing effect which might tend to loosen the holding power of the construction.

An important feature of the invention consists in a retaining member having a 70 rolling bearing, the axis of rotation being parallel to the axis of relative rotation of the tool and its support. This permits the relative movement desired and avoids undue wear upon the holding groove. 75

Another important feature of the invention is a spring having a hole and a ball mounted in the hole and held by the spring in contact with the groove to be engaged. Conveniently the ball is held between the 80 edges of the hole and a return bend of the spring and extends through the hole to cooperate with the groove. Preferably also the hole will be elongated in the direction in which the ball tends to move as the tool is 85 rocked, to permit the ball to roll on the edges of the hole and in the groove, thereby preventing undue wear on the groove and the ball.

These and other features of the invention 90 including certain details of construction and combinations of parts will be explained in connection with the accompanying drawings and then pointed out in the appended claims.

Figure 1 of the drawings is a side elevation of the tool carrying head of a machine in which the invention has been embodied.

Fig. 2 illustrates the tool and carrier separated.

Fig. 3 is a section on the line 3—3 of Fig. 1, and

Fig. 4 is a rear elevational view of the novel retaining member.

5 The tool operating shaft 10 is oscillated in its bearing 12 in any convenient way. It carries at its end the rotatable carrier 14 having two oppositely extending spindles 16. The carrier 14 has two operative positions, each of which brings one of the tools mounted on the spindles into the proper relation to the work. In practice a shank tool is mounted on one spindle and a forepart tool on the other. The latter is 15 illustrated at 18, and has the well-known groove 20 and notch 22 coöperating with the pin 24 on the carrier to prevent excessive rotation about the axis of the spindle 16. The old leaf spring form of retaining member is 20 shown at 26.

My novel retaining member is shown at 28. It consists of a leaf spring bent upon itself at 30, and having an oblong hole 32 in the rebent portion. In this hole is seated 25 a ball 34 the diameter of which is greater than the smaller dimension of the hole. The larger dimension of the hole is transverse to the axis of the spindle, as shown in Fig. 3.

As the tool is slightly rocked on the spindle by the turning of the shoe in the hands of the operator, the ball 34 rolls back and forth in the slot 32. Much of the torsional action on the spring is thus avoided, since the pressure exerted by the ball on the spring 35 has a shorter lever arm than is the case with the torsional stress exerted on such a spring as 26, and breakage is therefore largely reduced. At the same time, the rolling of the ball in the groove 20 wears it much less than 40 the scraping action characteristic of other forms of retaining members.

The ball 34 is arranged to engage the upper part of the notch 20 in order to hold the tool firmly in position.

45 Having described my invention, what I claim as new and desire to secure by Letters Patent of the United States is:—

1. A retaining member comprising a leaf spring having a hole and a ball seated in the 50 hole and held by the spring against the tool to be retained.

2. A retaining member comprising a spring re-bent upon itself and having a hole in one arm, and a bearing member seated in 55 the hole and confined between the arms.

3. A retaining member comprising a spring re-bent upon itself and having a hole in the re-bent portion, and a bearing member seated in the hole and confined between 60 the re-bent portion.

4. A retaining member comprising a spring re-bent upon itself and having an elongated hole in one arm, and a bearing member seated in the hole and confined between 65 the arms of the spring.

5. A retaining member comprising a spring re-bent upon itself and having a hole in one arm, and a ball seated in the hole and confined between the arms of the spring.

6. A retaining member comprising a 70 spring re-bent upon itself and having a hole in one arm, and a bearing member seated in the hole and confined between the sides of the hole and the other arm of the spring.

7. In a machine of the class described, a 75 spindle and a socketed member arranged to receive the spindle in the socket, the member having a groove substantially at right angles to the axis of the spindle, a resilient member mounted in connection with the spindle, having a hole and a ball held in the groove by the spring.

8. In a machine of the class described, a 80 spindle and a socketed member arranged to receive the spindle in the socket, the member having a groove substantially at right angles to the axis of the spindle, a resilient member mounted in connection with the spindle, having an elongated hole with its longer dimension substantially perpendicular to the 85 axis of the spindle, and a ball mounted in the hole arranged to engage the groove.

9. In a machine of the class described, a 90 spindle and a socketed member arranged to receive the spindle in the socket, the member having a groove substantially at right angles to the axis of the spindle, a re-bent member mounted in connection with the spindle having a hole in the re-bent portion having its 95 longer dimension perpendicular to the axis 100 of the spindle and a ball confined between the edges of the hole and the main arm of the spring, and extending through the hole to coöperate with the groove.

10. A retaining member comprising a 105 spring having a hole in it, and a ball mounted in the hole, the configuration of the spring being such as to confine the ball therein.

11. A retaining member comprising a leaf 110 spring having an elongated hole in it, and a ball mounted in the hole.

12. A retaining member comprising a 115 spring having a hole and a ball mounted in the hole, the diameter of the ball being greater than the least cross-dimension of the hole, and the spring having an extension arranged to hold the ball in the hole.

13. In a machine of the class described, a 120 spindle, an edge-setting tool mounted thereon for rotative movement around the axis of the spindle, and a retaining member for the tool having a roller bearing constructed and arranged to rotate around an axis parallel to the axis of the spindle.

14. In a machine of the class described, a 125 spindle, an edge-setting tool mounted thereon for rotative movement around the axis of the spindle, and a retaining member for the tool having an elongated hole extending 130

transversely to the axis of said rotative movement, and a ball mounted in the hole.

15. In a machine of the class described, a spindle, an edge-setting tool mounted thereon for rotative movement around the axis of the spindle, and a retaining member for the tool having a roller bearing con-

structed and arranged to rotate around an axis parallel to the axis of the spindle to permit small relative rotations between the tool and spindle.

In testimony whereof I have signed my name to this specification.

HENRY M. LOOMER.
